(57) **CLAIM**

The ornamental design of a lighting device, as shown and described.

DESCRIPTION

FIG. 1 is a top side angled perspective view of a lighting device in accordance with the present disclosure;

FIG. 2 is a rear view thereof;

FIG. 3 is a front view thereof;

FIG. 4 is a top view thereof;

FIG. 5 is a right side view thereof;

FIG. 6 is a left side view thereof; and,

FIG. 7 is a bottom side view thereof.

The broken line disclosure represents portions of the lighting device which form no part of the claimed design.
